UNITED STATES PATENT OFFICE.

JOHN BALLOU, OF SOMERVILLE, MASSACHUSETTS.

GRATE.

SPECIFICATION forming part of Letters Patent No. 286,574, dated October 16, 1883.

Application filed June 13, 1883. (No model.)

To all whom it may concern:

Be it known that I, JOHN BALLOU, a citizen of the United States, residing in Somerville, county of Middlesex, and State of Massachusetts, have invented a new and useful Improvement 5 in Grates, of which the following is a specification.

My invention relates to certain improvements in that class of grates commonly used 10 in cook-stoves or ranges.

The object of my improvement is to provide a grate which affords facilities for keeping the fire in proper condition with an economical 15 consumption of fuel, and it also allows the grate to expand and contract without undue strain upon any of its parts, all of which is explained more in detail in the following specification and accompanying drawings.

In the drawings, Figure 1 is a plan or top 20 view of the grate, and Fig. 2 is a longitudinal section through the center.

Similar letters refer to similar parts.

From the longitudinal bar *a*, which is the rear of the grate, a series of bars project parallel to each other and at right angles to the bar *a*, to the extreme front of the grate, with the usual spaces between the bars. The two outside bars—one at each end—are provided with studs or bearings *c* *e*, by which the grate 25 is supported in a manner so that it is nearly balanced, the rear being slightly heavier than the front part, and thus having a tendency to keep the grate in a level position when in use, and by which means the grate is permitted to tilt 30 in a manner common to grates of this class, one of the studs or bearings being adapted to receive a wrench or other suitable implement for the purpose of tilting the grate when required. By this mode of construction the 35 spaces between the bars at the front of the grate are open, each bar being free at the front end and independent of each other, and in consequence of this mode of construction the grate is permitted to expand and contract without 40 causing a strain upon any part of it. By this

mode of construction, also, a poker or other suitable implement may be thrust under the grate and between the bars, and the fuel gently lifted, thus admitting the air necessary for combustion without greatly disturbing the fire, while at the same time the fuel is not caused to fall through the grate, and thus become wasted, as by the ordinary mode of raking with a hooked poker. The absence of a longitudinal bar at the front or at the center 55 of the grate allows the fire to be aerated in the manner described, and with economical results.

In order to obtain the maximum of strength with the minimum of weight, the bars of the 60 grate, at their underneath side, are provided with double longitudinal ribs; or, in other words, are grooved out, as shown in the sectional drawings, Fig. 2, thus allowing a free circulation of air around the bars, and obviating the tendency to warp. 65

The grate may be rectangular, square, or of any other shape, depending, of course, upon the style or shape of the stove or range for which it may be specially designed. 70

I am aware that grates have been constructed in a manner so that the transverse bars were independent of each other at the front of the grate, and also that double ribbed or grooved bars have heretofore been used; hence I make 75 no broad claim to these special features as distinct elements of my invention.

I claim—

The combination, in a grate, of a longitudinal rear bar, a series of double ribbed or 80 grooved bars extending at right angles to the rear bar, and the studs or bearings *c* and *e*, located at or near the center of the outside bars, in the manner and for the purpose substantially as set forth.

JOHN BALLOU.
